PACKAGE HANDLE OR THE LIKE

Gustave Alfano, 141-15 28th Ave.,
Flushing, N.Y. 11354

Filed Apr. 16, 1969, Ser. No. 16,763

Term of patent 7 years

Int. Cl. D9—99

U.S. Cl. D9—292

FIG. 1.

FIG. 2.

5 → FIG. 3.

FIG. 5.

FIG. 7.

FIG. 6

7 →

FIG. 4

FIG. 1 is a top perspective view of a package handle or the like showing my new design;

FIG. 2 is a bottom perspective view;

FIG. 3 is another top perspective view showing the package handle in an operative position with the ends turned downwardly;

FIG. 4 is a view similar to FIG. 3, but showing the bottom and with the ends turned downwardly in operative position;

FIG. 5 is a sectional view taken on the line 5—5 of FIG. 3;

FIG. 6 is a top perspective view of another embodiment of my new design; and

FIG. 7 is a sectional view taken on the line 7—7 of FIG. 6.

I claim:

The ornamental design for a package handle or the like, as shown and described.
